UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

LOCKING GUIDE FOR SWINGABLE DOORS

Application filed December 19, 1929. Serial No. 415,286.

The invention relates to hingeable doors for a railway car forming a part of the load retaining means therefor and may be used in connection with the drop doors of hopper 5 cars, general service gondola cars, ballast cars, ore cars or in connection with drop end doors for mill type gondola cars or the swingable side walls of ballast cars, or in fact, may be used in the place of any hinge in a 10 railway car.

The object of the invention is to provide a guide for such doors which protrudes through an aperture in a beam, floor or other part of the car and is formed with a hinging 15 surface which engages one edge of the aperture during its swinging movement and is also provided with an outer arcuate surface positioned to engage another edge of the aperture to guide the door during its swinging movement.

Another object is to provide the guide with a removable projection (which is attached after the guide is projected through the aperture) with the width of the guide and 25 projection exceeding the width of the aperture so that the guide is locked in place upon the car.

Another object is to eliminate the usual hinge butts and hinge pins.

30 In the drawings:

Figs. 1, 2, 3 and 4 show the invention used in connection with the drop end door or gate of a mill type gondola car.

Figs. 5 and 6 show the invention used in 35 connection with the drop door of a general service car.

Figs. 7 and 8 show the invention used in connection with a hopper car.

Fig. 9 shows a door with the invention applied thereto.

Figs. 1 and 2 show the invention used in connection with the drop end door of a mill type gondola car, wherein 2 is the floor and 3 is the end sill angle. The floor is provided 45 with an aperture 4 through which the guide 5 protrudes, which guide is cast integral with or secured to the drop door. The aperture is slightly wider than the guide 5 and after the guide is inserted through the aperture the 50 rivet, bolt or other projection 6 is secured

to it so that the width of the guide and projection exceeds the width of the aperture whereby the guide can not be removed from the aperture until the projection is removed from the guide. The guide is provided with a laterally extending part 7 forming a surface 8 engaging one end of the aperture as the door is moved from closed position, shown in Fig. 1, to open position, as shown in Fig. 2. The guide is also formed with an outer 55 60 arcuate surface 9 positioned to engage the opposite edge of the aperture and guide the door during its swinging movement. With this arrangement the door is held in the proper position, both longitudinally and laterally 65 of itself, in its open and closed position and in any position therebetween.

The size of the aperture 4 in the floor is such that as the door is swung upwardly to closed position the guide 5 moves the door 70 into engagement (or substantially so) with the end sill angle 3, which angle projects above the floor and forms an abutment for the door between the spaced apart side walls and preferably relieves the guides 5 of stresses 75 imposed upon the door by shifting cargos. The door is substantially the same width as the aperture 4 so that the door effectively closes the opening against leakage of ladings, such as sand or chads.

Figs. 1 and 2 illustrate a cast metal door having the guide cast integral therewith, while Fig. 3 shows a separate door 11 having the locking guide 12 secured thereto.

Fig. 4 shows a car having a wooden floor 85 15 provided with a large opening 16 which is partially closed by the application of the plate 17 after the locking guide is projected through the aperture.

Figs. 5 and 6 show the invention used in a 90 general service car in which the floor comprises a plurality of horizontally positioned doors 20 hinged to the center construction 21. In the form illustrated the center sill 21 is provided with an aperture 22 through 95 which the locking guide 23 protrudes and the cover plate 24, which forms a part of the floor, is extended beyond the center sill to overlap the door 20. Any convenient stop may be used to limit the downward movement 100

of the door. These doors usually swing about thirty degrees. The locking guide 23 supports the door when in dropped position and when the door is closed the locking guide 5 retains the door in its proper relative position to the sill.

Figs. 7 and 8 show the device used in connection with a hopper car which is provided with slope sheets 30 forming a hopper having a stiffening beam 31 adjacent the lower edge. In my arrangement this stiffening beam 31 is provided with an aperture 32 through which the locking guide 33 projects and the sloping floor 30 extends beyond the 10 stiffening beam and partially overlaps the door 34. The locking guide supports the door during its entire swinging movement, as well as in open and closed position.

The accompanying drawings illustrate the 20 preferred form of the invention, though it is to be understood that the invention is not limited to the exact details of construction shown and described, as it is obvious that various modifications thereof, within 25 the scope of the claims, will occur to persons skilled in the art.

I claim:

1. In a railway car, the combination of a 30 car part having an aperture, a door provided with a guide projecting through the aperture, said guide having a laterally extending part forming a hinging surface with one edge of the aperture, said part having a removable lateral projection with the width 35 of the guide and projection exceeding the width of the aperture whereby the guide can not be removed from the aperture until the projection is removed from the guide.

2. In a railway car, the combination of a 40 car part having an aperture, a door provided with a guide projecting through the aperture having a laterally extending part forming a hinging surface with one edge of the aperture, said part having a removable lateral 45 projection with the width of the guide and projection exceeding the width of the aperture whereby the guide can not be removed from the aperture until the projection is removed from the guide, said guide having an outer arcuate surface positioned to engage another edge of the aperture to guide 50 the door during its swinging movement.

3. In a railway car, the combination of a 55 car part having an aperture, a floor having a portion projecting beyond the car part, and a door underlying said portion and provided with a guide projecting through the aperture, said guide having a laterally extending part forming a hinging surface with one 60 edge of the aperture, said part having a removable lateral projection with the width of the guide and projection exceeding the width of the aperture whereby the guide can not be removed from the aperture until the projection is removed from the guide.

4. In a railway car, the combination of spaced apart side walls, a floor, an abutment projecting above the floor and extending between the side walls, an aperture in the floor adjacent the abutment, and a door provided with a guide projecting through the aperture, 70 said guide having a laterally extending part forming a hinging surface with one edge of the aperture and an outer arcuate surface positioned to engage the abutment to guide the 75 door into engagement therewith when in upright position.

5. In a railway car, the combination of a floor having an aperture therein, and a door provided with a guide projecting through the 80 aperture, said guide having a laterally extending part forming a hinging surface with one edge of the aperture, said door being substantially the same width as the aperture whereby the aperture is substantially closed 85 when the door is in upright position.
